UNITED STATES PATENT OFFICE.

JOSEPH W. BOND, OF PHILADELPHIA, PENNSYLVANIA, ASSIGNOR TO UNDERWOOD TYPEWRITER COMPANY, OF NEW YORK, N. Y., A CORPORATION OF DELAWARE.

TYPEWRITING-MACHINE.

1,364,974.

Specification of Letters Patent. Patented Jan. 11, 1921.

Application filed August 23, 1919. Serial No. 319,300.

To all whom it may concern:

Be it known that I, JOSEPH W. BOND, a citizen of the United States, residing in Philadelphia, in the county of Philadelphia and State of Pennsylvania, have invented certain new and useful Improvements in Typewriting-Machines, of which the following is a specification.

This invention relates to typewriting machines, and more especially to such machines as are provided with key-operated tabulating mechanism.

The keys for operating the tabulating mechanism are often separate from the character keys which make up the typewriter keyboard, and in the Underwood typewriting machine are frequently placed at the very front of the machine, just outside of the front bar of the frame, and 20 usually a little below the top of said bar. When the tabulator keys are located here, there is some danger that the typist's apparel may become entangled with them, especially the sleeve. To prevent this, I 25 have provided a shield which overlies the tabulating keys. Moreover, the shield, by covering up the keys, minimizes the number of keys before the eye, or within the reach of the typist's fingers, with the result that, 30 when the shield overlies the tabulator keys, there will be eliminated the confusion which an inexperienced typist may have in using a machine with tabulating keys.

The shield may be pivoted to the frame 35 of the typewriter, so that it may be easily swung to and from effective position. Where the shield is located at the front of the frame in the Underwood typewriting machine, the shield may advantageously 40 take the form of a sheet of metal having bent-over ends, the latter adapted to form journals for pivots in ears fast to the frame of the typewriter. These ears, instead of being separately fast to the frame, may take 45 the form of the ends of a light frame which is adapted to be made fast to the typewriter frame, the ears and the piece joining them being conveniently stamped out of a piece of sheet-metal at substantially a single operation. The shield itself and the ears by 50 which it is journaled on its pivots may likewise be stamped from a single sheet of metal. Thus, it will be seen that my struc-

ture provides a simple, cheap and effective shield or guard for the tabulating keys. 55

Other features and advantages will hereinafter appear.

In the accompanying drawings,

Figure 1 is a fragmentary side view of an Underwood standard typewriting machine, 60 showing the present invention as applied thereto.

Fig. 2 is a spread perspective of the shield and the mounting for it.

Fig. 3 is a fragmentary view similar to 65 Fig. 1, but showing the shield swung down to ineffective position.

Fig. 4 is a fragmentary front view of the parts seen in Fig. 1, the keyboard of character keys being omitted. 70

In the Underwood typewriting machine, the frame 10 comprises character keys 11, which, when depressed, are adapted to cause types, not shown, to print upon the usual platen, not shown, which is journaled in the 75 usual carriage, not shown. The machine also comprises a space-bar 12, which is adapted to feed the carriage along by letter-space movements. The Underwood typewriting machine also frequently includes 80 decimal tabulator keys 13 on the front ends of key-levers 14, which, when depressed, are adapted to release the carriage and bring it to rest at any desired point in its travel, one form of this mechanism being shown 85 in the patent to Alfred G. F. Kurowski, No. 1,106,950, dated August 11, 1914.

The tabulator keys 13 usually stand just in front of a front cross-bar 15 forming a part of the frame 10. The key-levers 14 90 are pivoted intermediate their ends at a point not shown, with the result that the keys 13 are rather easily vibrated, and, where no comb for holding them is provided, they may be accidentally bent out of 95 position. To protect the keys from this bending, as well as from the liability of entanglement described above, a shield or shutter 16 pivoted upon pivots 17 is adapted to be swung over the keys 13, so as to little 100 more than clear them, with the result that the upper surface of the shield 16 forms a continuous or smooth surface not liable to catch in the apparel of the typist, and not liable to confuse the inexperienced typist, 105 as the keys 13 may sometimes do. The

pivots 17, upon which the shield 16 is journaled, may be in the form of pins or projections projecting from ears 18 formed as the ends of a connecting piece 19 made of metal.

5 Any convenient means may be used for attaching the ears 18 to the typewriter frame. As herein illustrated, the ears 18 are each provided with an inwardly-turned lug 20 and an outwardly-turned lug 21, provided with screw holes through which screws 22 may be threaded into the front bar 15. The arrangement of screws and lugs thus described forms a mounting for the pivots 17, which can be made out of very light 10 metal and yet be extremely rigid, owing to the stiffening function of the connecting piece 19. Normally, the shield 16 may be held in the Fig. 1 position in which it covers the tabulator keys 13, and may be detained 15 there by a detent in the form of a leaf spring 23 stamped out from the metal body of the shield body 16, and adapted to seat itself in a hollow 24 of the right-hand ear 18. The shield 16 may be prevented from 20 swinging too far rearwardly by a stop projection or pin 25, and when swung down to the Fig. 3 position may be arrested by a second pin or lug 26, which will hold the 25 swung-down shutter 16 clear of the overhanging tops 27 of the tabulator keys as they descend in operation.

To give the shutter sufficient strength to stand considerable blows, and thus thoroughly protect the tabulator keys, the front 30 edge thereof may comprise a downwardly-projecting web 28, which serves to stiffen it. The body of the shield 16 is journaled upon the pivot pins 17 by means of ears 29 which are formed as integral bent-over 35 extensions of the metal of which the shield is formed, so that the shield body 16, the spring 23, the web 28 and the ears 29 may be stamped from a single piece of sheet-metal.

40 Variations may be resorted to within the scope of the invention, and portions of the improvements may be used without others.

Having thus described my invention, I 45 claim:

50 1. In a typewriting machine, the combination with a typewriter frame, of character keys in said frame forming a keyboard, a row of tabulator keys, a bar forming part of the typewriter frame between the keyboard and the tabulator keys, and a device mounted on said frame to occupy a position in front of said bar, to provide a continuous surface over said tabulator keys but movable clear of them to enable them to be operated.

60 2. In a typewriting machine, the combination with a typewriter frame, of character keys in said frame forming a keyboard toward the front of the frame, a row of tabulator keys in front of the keyboard, a bar forming part of the typewriter frame be-

tween the keyboard and the tabulator keys, and a cover pivoted upon the bar adapted to rest above the tabulator keys to shield them, and adapted to be swung down clear of them to enable them to be operated.

70 3. In a typewriting machine, the combination with a typewriter frame, of character keys in said frame forming a keyboard toward the front of the frame, a row of tabulator keys below and in front of the frame 75 and below the top of the adjacent top of the frame, ears fast to said frame, and a shield for the tabulator keys pivoted upon said ears and adapted to be swung forward thereon to clear the keys to permit them to be 80 operated.

4. In a typewriting machine, the combination with a typewriter frame, of character keys in said frame forming a keyboard toward the front of the frame, a row of 85 tabulator keys having enlarged tops and located adjacent the front of the frame and below its top, a shield for the tabulator keys, pivots for said shield fast to said frame, a detent for holding the shield in its 90 upper effective position, and a stop for arresting the shield clear of the path of the depressed tops of the tabulator keys.

5. In a typewriting machine, the combination with a typewriter frame, of character 95 keys in said frame forming a keyboard, a row of tabulator keys, and a shield clear of the character keys and pivoted in said frame, so as to rest above the tabulator keys and cover them, and adapted to be swung on 100 its pivots clear of them to enable their free operation.

6. In a typewriting machine, the combination with a typewriter frame, of character keys in said frame forming a keyboard, 105 a row of tabulator keys, a flat sheet-metal shield adapted to overlie said tabulator keys, comprising bent-down ears integral with the shield, and an overhanging web forming one edge of the shield adapted to give it 110 strength, and the whole struck from a single piece of sheet-metal.

7. In a typewriting machine, the combination with a typewriter frame, of character keys in said frame forming a keyboard, 115 a row of tabulator keys, a shield adapted to lie above said tabulator keys, and a support for said shield comprising pivots, ears upon which the pivots are carried, a connecting member connecting the ears, and a bent-over 120 lug on each ear, the whole stamped from a single sheet of metal.

8. In a typewriting machine, the combination with a typewriter frame, of character keys in said frame forming a keyboard, 125 a row of tabulator keys, a shield adapted to overlie said tabulator keys, a sheet-metal body forming the main part of said shield, ears struck from said sheet-metal and adapted to form journals for the shield, a 130

turned-over edge at one edge of the shield forming a strengthening web, fixed ears comprising pivots on which said shield is journaled, a connecting member connecting 5 said fixed ears, and a lug projecting from each fixed ear, said last-named ears, connecting member and lugs adapted to be struck from a single piece of sheet-metal.

9. In a typewriting machine, the combination with a typewriter frame, of character keys in said frame forming a keyboard, a row of tabulator keys in front of said frame, a shield adapted to lie over said tabulator keys and comprising a cover plate and 10 depending ears at the ends of said row of tabulator keys, said ears being provided with journals, fixed ears upon said frame corresponding to the depending ears of said shield, pivots upon said fixed ears coöperating 15 with the journals in the ears of said shield, an abutment upon one of said fixed ears, and a spring detent upon said shield adapted to coöperate with said abutment to maintain the shield in elevated position.

25 10. In a typewriting machine, the combination with a typewriter frame, of character keys in said frame forming a keyboard, a row of tabulator keys in front of said frame, a shield adapted to lie over said tabulator 30 keys and comprising a cover plate and depending ears at the ends of said row of tabulating keys, said ears being provided

with journals, fixed ears upon said frame corresponding to the depending ears of said shield, pivots upon said fixed ears coöperating 35 with the journals of the ears of said shield, an abutment upon one of said fixed ears, a spring detent upon said shield adapted to coöperate with said abutment to maintain the shield in elevated position, and 40 stops upon said fixed ears coöperating with said depending ears to limit the movement of said shield.

11. In a typewriting machine, the combination with a typewriter frame, of rows of 45 character keys positioned in said frame, a row of tabulator keys, and a shield pivoted with respect to the frame and comprising a plate adapted to lie over the tabulator keys and to cover and uncover said keys, said 50 plate being of a width substantially the same as the tabulator keys and at a height below the level of the next higher row of keys so as not to interfere therewith.

12. In a typewriting machine, the combination with a typewriter frame, of rows of 55 keys positioned in said frame, and a shield pivoted with respect to the frame and adapted to lie over one row of keys to separate said row from the remaining rows.

JOSEPH W. BOND.
